SURGICAL BANDAGE

Laura M. Pegg, Detroit, Mich.

Application July 8, 1941, Serial No. 401,498

2 Claims. (Cl. 128—155)

This invention relates to improvements in surgical abdominal bandages designed for use following operations and adapted to be secured about the body of the patient over the wound dressing and to properly support the body adjacent to the incision; and also to properly support the internal organs without undue restraint or compression at any particular point upon the body.

Heretofore it has been a practice in hospitals to provide a band or abdominal bandage of substantial width and length and to wrap such band tightly about the body of the patient over the wound dressing, but due to the varying contours of the body and width of the band such band exerted substantially greater compression about the body at certain points than at others.

The circumference of the body varies substantially up and down adjacent the waist line and a wide bandage when tightly wrapped to properly support the body adjacent an abdominal incision and to properly support the internal organs necessarily tends to bind at some places substantially more than at others.

My improved bandage is particularly designed to overcome the above disadvantage. It is designed to properly and securely support the body adjacent the incision and to also properly support the internal organs. It is of such a character that it conforms to the varying contours and dimensions of the body when wrapped thereabout and exerts a snug restraining effort upon the body at all places without binding appreciably more at one point than another. It is further designed to accomplish the proper support and snugly engage the body while permitting movement of the body without dislocation of the bandage.

Other objects, advantages, and meritorious features of my improved band or bandage will more particularly appear from the following description, appended claims, and accompanying drawing, wherein:

Figure 1 is a plan of a bandage embodying my invention.

Fig. 2 is a cross-sectional view taken on line 2—2 of Fig. 1.

Fig. 3 is a plan showing my improved bandage partially wrapped about a fragment of the body as shown in dotted outline.

Fig. 4 shows my improved bandage completely wrapped about a fragment of a body, and

Fig. 5 is a cross-sectional view through the bandage shown in Fig. 4.

My improved bandage is formed of suitable fabric cut to the required size and consists of a

5 plurality of thicknesses of material. In one preferred form two plies or two thicknesses of materials are used and such are shown in the figures of the drawing. These thicknesses are co-terminous in size and generally elongate, being of a substantially rectangular shape which is here shown as having a length approximately three times its width. The intermediate portions 20 of the two thicknesses are secured together as by 10 stitching 22 forming a back section which is adapted to overlie the back of the wearer.

The back section is provided with complementary end portions throughout which the two thicknesses are not secured together. These end 15 portions have a width substantially equal to that of the back section and a length substantially equal thereto. The end portions are adapted to wrap over the sides and abdomen of the wearer and are of a length sufficient to accomplish such 20 function.

Each thickness of each end portion is divided 25 lengthwise into a plurality of strips, three being here shown. These strips extend outwardly from the back section and possess an aggregate width substantially equal to that of the back section. The strips are here shown as identified by numbers from 1 to 12.

When the bandage is placed about the body the back section is disposed to overlie the back of the 30 wearer and the strips of the first thickness are wrapped over the sides and across the abdomen as shown in Fig. 3. They are wrapped thereover slightly at an angle so that corresponding strips of the complementary end portions are overlapped and interlaced substantially completely 35 covering the abdomen and sides of the patient. It is preferable to wrap such strips at a slight angle to increase their adherence to each other though this is accomplished primarily by using a 40 material such as flannelette which has a soft nap on its surface that when strips formed therefrom are overlapped in interlaced relationship they resist any pulling out with a considerable degree of tenacity. I prefer to use in my bandage material having such a nap on its surface rather than to use ordinary bandage gauze or a hard finish material.

Following the overlapped wrapping of the strips 1—6 as numbered in the figures of the drawing, the second thickness and its strips 7—12 are then drawn across the sides and body of the wearer and the angle of overlapping may be substantially greater as shown in Fig. 4.

It has been found that the tenacity of adherence between the overlapped interlaced strips is

so high that it is not necessary to do more than to pin the two uppermost strips as shown in Fig. 5 with safety pins 24. In some instances the bandage has been used without any pinning at all and it has also been entirely satisfactory.

It is apparent that bandages might be provided in varying sizes and shapes and with different kinds of materials suitable to the use and that improvements might be made therein without departing from the spirit of the invention other than as set forth in the claims.

What I claim:

1. A surgical bandage comprising two corresponding thicknesses of bandage fabric in elongate form, said thicknesses secured together intermediate their ends forming a back section, said thicknesses not being secured together throughout their end portions, each thickness of each end portion divided into a plurality of strips extending outwardly from the back section and

having a length substantially equal thereto and having in the aggregate a width substantially equal thereto.

2. A surgical abdominal bandage having a back section adapted to overlie the back of the wearer, complementary end portions extending from opposite margins of the back section adapted to wrap about the sides and over the abdomen of the wearer, each end portion comprising two thicknesses of fabric having a soft nap surface, each thickness divided into a plurality of strips extending outwardly from the back section and having a length substantially equal thereto, said strips adapted to be wrapped over the sides with the strips of one thickness of each end portion interleaved between the strips of the two thicknesses of the other end portion, back of the wearer and to adhere snugly when wrapped in overlapping relationship.
